OSCAR H. PIEPER, OF ROCHESTER, NEW YORK.

COMBINED TOOL HANDLE AND SWITCH.

Application filed December 12, 1924. Serial No. 755,575.

This invention relates to combined tool handles and switches for operating electrical hand tools, such, for example, as a dental cautery, the chief object of the invention being 5 to provide an improved instrument of this nature operating in a simple and convenient manner and having a practical form of construction comprising comparatively few parts capable of being economically manufactured 10 and readily assembled by unskilled labor.

To these and other ends the invention resides in certain improvements and combinations of parts, all as will be hereinafter more 15 fully described, the novel features being pointed out in the claims at the end of the specification.

In the drawings:

Figure 1 is a general view of an instrument embodying the present invention;

Figure 2 is a sectional view on the line 2^a—2^a in Figure 1, showing the interior operating parts;

Figure 3 is a view similar to Figure 2, but with the parts in different position and additionally sectioned;

Figure 4 is a similar view in a sectional plane at right angles to that of Figures 2 and 3;

Figure 5 is a transverse sectional view on the line 5^a—5^a in Figure 3, and

Figure 6 is a fragmentary detail of a portion of the tubular handle.

Similar reference numerals throughout the several views indicate the same parts.

The invention is disclosed in the present instance by way of illustration in an embodiment adapted for use with dental hand tools, such as a cautery, comprising the handle portion proper indicated generally at 10, and a portion 11 of the usual or any suitable construction known in the art for mounting the tool itself. As shown, the tool mount 11 is attached to one end of the handle portion, the other end of which receives the electrical 45 conductors for energizing the tool under control of the handle switch.

The handle comprises preferably a main tubular portion 12 constructed of a suitable material with relatively thin walls throughout the major portion of its extent but thickened somewhat at the tool end as at 13. This end is adapted to have the end of the tool mount 11 detachably secured therein for which purpose the latter is provided with a lug 14 cooperating with a bayonet slot, of the

usual or any suitable construction (not shown), comprising an inclined shoulder or surface 15 in the handle so that the tool mount after insertion in the latter may be turned to bring lug 14 into cooperation with shoulder 15 and thus securely draw the tool mount down to its seat in the handle, as well understood in the art.

The end of the tool mount in the handle carries a projecting contact post 16, Figure 65 3, surrounded in insulated relation by a shorter conducting sleeve 17, these conducting portions extending through the tool mount into connection with suitable contacts for co-operation with the tool inserted in the mount. 70

Within the handle tube 12 is a core piece 18 of any suitable insulating material and of slightly less diameter than the bore of the tube, with longitudinally extending slots 19. These slots are for the purpose of receiving 75 contact strips 20 and 21 of resilient conducting metal placed in the bottom of the slots and covered by protective insulating strips 22 and 23, respectively. These strips are detachably retained in their slots by means of 80 a dowel pin 24 and by U-shaped collars 25 fitted over the same in circular grooves 26 in the core piece. These securing means are readily applied and removed by hand without the use of tools and securely hold the contact and insulating strips in the core piece 85 slots. The core piece with its contacts thus assembled is readily inserted through the end of the handle tube opposite the tool and is secured in proper position in the tube by means 90 of a screw 27 passed from the outside through the tube wall and into a threaded opening 28 in the core.

The ends of contact strips 20 and 21 opposite the tool have connected therewith the 95 wires 29 and 30, respectively, of an electric circuit of suitable power, these wires passing in a cord 31 through an opening in a plug 32 detachably screwed into this end of the handle tube and equipped outside the latter with a 100 suitable flexible guard 33 for the circuit cord.

The contact strips 20 and 21 cooperate at their other ends with the contact elements 17 and 16, respectively, of the tool mount. Contact strip 20 is extended for continuous engagement with contact sleeve 17 against which it bears through its inherent resilience so long as the tool mount is attached to the handle. Contact strip 21 is extended opposite the end of contact rod 16, but normally stands spaced 110

therefrom as shown in Figure 2. For this purpose the contact strip is bent near the adjacent end of the core piece so as to lie inclined to the axis of the handle, as at 34, Figure 3. 5 The contacts 16 and 21 thus form a pair of self opening contacts operated by the means hereafter described.

The means for operating the switch contacts is simple and effective, comprising a 10 member or sleeve 35 sliding longitudinally on the handle tube as shown. This sleeve is preferably constructed of insulating material with a thickened central portion 36 formed with a transverse bearing opening in which slides a 15 member of plunger 37, also of insulating material. The latter projects at its outer end from the sleeve boss 36 as shown and at its inner end has a head 38 engaging the outwardly inclined portion 34 of the switch contact 21 20 which normally presses the plunger outwardly until its head 38 engages the inner walls of the handle tube. The latter is formed with a longitudinal slot 39 in which the plunger works and which limits movement of the 25 sleeve. The core piece is reduced in diameter for clearance in this neighborhood as at 40, except for an end portion 41 slotted to receive and guide the contact strips 20 and 21. End portion 40 is also slabbed off opposite the 30 plunger as at 42 to clear the latter.

It is apparent from this construction that with the sleeve 35 in the position shown in Figure 2 plunger 37 may be conveniently depressed and released by a thumb or finger of 35 the hand holding the handle to temporarily close and open the switch, as desired in the operation of the instrument. On the other hand when it is desired to close the contacts and maintain them for a period in closed position, 40 this is conveniently accomplished by merely sliding sleeve 35 longitudinally on the handle toward the tool end, in which movement the plunger, sliding along the inclination of the contact 21, presses the inturned outer end 45 thereof into engagement with the cooperating contact 16. The switch thus remains closed without holding the plunger so long as sleeve 35 remains in this outer position, but is again opened by sliding the sleeve longitudinally in 50 the opposite direction.

It will be seen from the above description of the construction and operation of the instrument that the invention provides in combination with a tool handle of compact and 55 pleasing proportions, an exceedingly convenient switch which may be operated intermittently by merely depressing plunger 37 or maintained closed for a desired period by merely sliding sleeve 35 longitudinally of 60 the handle, both of these operations being easily accomplished by a thumb or finger of the hand grasping the handle. The construction is furthermore simple, reliable and practical in character requiring but few parts

65 economical to manufacture and which may be readily assembled by unskilled labor.

I claim as my invention:

1. In a combined electric tool handle and switch, a hollow tool handle containing a pair of self-opening contacts and actuating 70 means therefor on said handle comprising a pair of members having a relative movement for temporarily closing said contacts in one position and also a movement together to another position for automatically closing said 75 contacts and holding the same closed.

2. In a combined electric tool handle and switch, a hollow tool handle containing a pair of self-opening contacts one of which is fixed 80 within the handle and the other movable therein and relative thereto, a member adapted to be depressed against the action of said movable contacts to temporarily close the same, and a second member carrying the first member and movable on the handle whereby 85 said first member will automatically close said contacts and maintain the same closed.

3. In a combined electric tool handle and switch, a hollow tool handle containing a pair of relatively movable contacts, a plunger disposed outwardly of said contacts and adapted to be depressed inwardly of the handle against the action of one of said contacts for temporarily closing the same, and a sleeve carrying 95 said plunger and movable longitudinally of the handle said movement causing the plunger to effect closing said contacts and maintaining the same closed. 95

4. In a combined electric tool handle and switch, a hollow tool handle containing a 100 pair of switch contacts one having an inclination to the handle axis and a resilient self-opening action, a member adapted to be depressed against the action of said resilient contact to temporarily close said contacts, and a second member carrying said first member and movable longitudinally of the handle with said first member in cooperation with the inclination of said contact for closing the contacts and maintaining the same closed. 105

5. In a combined electric tool handle and switch, a hollow tool handle containing a pair of switch contacts one having an inclination to the handle axis and a resilient self-opening action, a plunger adapted to be depressed inwardly of the handle against said resilient contact to temporarily close the contacts, and a sleeve carrying said plunger and slidably longitudinally of the handle with said plunger in cooperation with the inclination of said 110 contact to move the latter to closed position and hold it closed. 115

6. In a combined electric tool handle and switch, a hollow tool handle, a pair of fixed contacts therein, a core piece in said handle carrying a pair of spring contacts with one of the same engaging one of said fixed contacts and the other inclined to the handle 125

axis and normally spaced from said other fixed contact, a finger piece depressible inwardly of the handle against said spaced spring contact to temporarily engage the 5 same with its fixed contact, and a member carrying said finger piece and movable longitudinally of the handle with said finger piece in cooperation with the inclined portion of said contact to move the same to and retain it 10 in closed position.

7. In a combined electric tool handle and switch, a hollow tool handle, a pair of contacts therein, a longitudinally slotted core piece detachably inserted in said handle, a 15 pair of spring contacts detachably secured in the slots of said core piece with one thereof in engagement with one of said first contacts and the other inclined to the handle axis and normally spaced from the other of said first 20 contacts, a sleeve slidable longitudinally of the handle and having a transverse bearing therein, and a plunger sliding in said bearing and in a longitudinally extending slot in said handle in cooperation with said inclined 25 contact for temporarily closing the switch and for holding the switch closed when said sleeve is moved longitudinally on the handle.

8. In a device of the class described, a hollow handle, a pair of contacts disposed with- 30 in the handle, one of which is fixed and the

other movable to engage the same, said movable contact having a portion inclined to the axis of the handle, a control member movable to different positions on the handle, and a second member movable on the control mem- 35 ber transversely of the axis of the handle and arranged when the control member is moved to one position to move relative thereto through engagement with the inclined portion of said movable contact, and serving to 40 move said contact to closed position.

9. In a device of the class described, a hollow handle, a pair of contacts disposed within the handle, one of which is fixed and the other movable to engage the same, said movable 45 contact having a portion inclined to the axis of the handle, a control member movable to different positions on the handle, and a second member movable on the control member transversely of the axis of the handle and 50 arranged when the control member is in one position to be manually forced inwardly to engage and close the movable contact and adapted during movement of the control member to another position to automatically 55 shift the movable contact to closed position through engagement with the inclined portion thereof.

OSCAR H. PIEPER.
